(57) **CLAIM**

The ornamental design for a bracelet, as shown and described.

DESCRIPTION

1. Bracelet

1.1 : Perspective

1.2 : Front

1.3 : Back

1.4 : Right

1.5 : Left

1.6 : Top

1.7 : Bottom

The bracelet comprises a ribbon-like element, the ends of which have a reduced width and are interconnected by a square clasp. The ribbon-like element has an embossed section on the outer surface thereof, resembling a horse bit.
